UNITED STATES PATENT OFFICE.

CHARLES STOLBERG, OF TOLEDO, OHIO, ASSIGNOR TO AMERICAN CAN COMPANY, OF NEW YORK, N. Y., A CORPORATION OF NEW JERSEY.

SHEET-METAL SAP RECEPTACLE OR VESSEL.

No. 857,846.

Specification of Letters Patent.

Patented June 25, 1907.

Application filed February 8, 1907. Serial No. 356,296.

To all whom it may concern:

Be it known that I, CHARLES STOLBERG, a citizen of the United States, residing in Toledo, in the county of Lucas and State of Ohio, have invented a new and useful Improvement in Sheet-Metal Sap Receptacles or Vessels, of which the following is a specification.

My invention relates to improvements 10 in the construction of one piece sheet metal receptacles of rectangular form commonly used for collecting sap and other purposes, and which are made with integral bottom, sides and ends from a single sheet metal 15 blank by forming suitable folds thereon. Heretofore such one piece receptacles have usually been made by providing the blank at each end at the middle part thereon with outwardly projecting tongues or lips which 20 are turned or folded outwardly over the upper edges of the end walls of the receptacle to lock or bind together the angle folds of the blank at the ends of the receptacle, and as a consequence, there is considerable waste 25 of stock as these projecting lips or tongues materially increase the length of the blank and the amount of the stock of sheet metal required to cut or form it.

The object of my invention is to provide 30 an improved construction by which the waste of stock may be obviated and the one piece receptacle formed of minimum amount of stock.

My invention consists in the means I 35 employ to practically accomplish this object or result as herein shown and described and more particularly pointed out in the claims.

In the accompanying drawing forming a 40 part of this specification, Figure 1 is a front elevation showing perspectively a sheet metal sap receptacle embodying my invention. Fig. 2 is a central vertical cross section. Fig. 3 is a central vertical longitudinal section. Fig. 4 is an end view. Fig. 5 is a 45 plan view of the sheet metal blank in the flat showing in dotted lines the angles or lines upon which the folds are made to form the receptacle from the flat blank, and also showing in broken lines surrounding the blank the

form and size of the blank heretofore employed in making the same sized receptacles in the old way and thus the relative amount of stock saved by my invention. Fig. 6 is a plan view showing one end portion of the blank partially formed or folded as it appears 50 after the first step of the operation of folding or forming it into the receptacle shown in Figs. 1 to 4.

In the drawing, A represents a sap bearing tree, B a sheet metal apron inserted in the 60 cut a of the tree.

D is the one piece sheet metal receptacle embodying my invention, the same comprising a bottom d, upright sides d¹ and flaring ends d², the latter having angle folds d³ d⁴, 65 one overlapping the other at the upper part thereof, clamped or held in place by the integral locking lips d⁵ on the outer angle fold d⁴ which lips are folded or turned inward over the upper edge of the flaring ends d². 70 All these parts of the receptacle D are integral with each other and formed from a single flat sheet metal blank D¹ by forming suitable bends or folds therein. The bends d⁶ surround the bottom d, the bends d⁷ are at 75 the upwardly extending edges of the flaring ends d². The angle folds d³ d⁴ overlap each other at the flaring ends d² of the receptacle, and are held or locked in place by the integral locking lips d⁵ which are formed at the corner 80 portions of the blank D¹ out of stock that would otherwise be cut away as waste, as will be readily understood from Fig. 5 of the drawing. By thus forming the clinging or locking lips d⁵ at the upper edge of one member of the angle folds d⁴ so that said lips come at the corner portions of the blank D¹ instead of at the ends thereof as shown by the outer broken line D² representing the blank heretofore used in the old way, I make a material 85 saving in the amount of stock required to produce the receptacle D.

To stiffen and strengthen the integral upright sides d¹ of the receptacle at the upper edges thereof, the same are preferably provided with integral rolls or curves d⁸ d⁹, one of which is preferably turned inward to form a hook edge to engage the downwardly and

upwardly turned supporting hook or edge b at the lower longitudinal edge of the apron B. The sheet metal apron B preferably has at its ends upturned flanges b^1 and a concavely curved upper edge b^2 .

I claim:—

A one piece sheet metal receptacle having integral bottom sides, ends and angle folds,

the angle folds having integral locking lips turned over the upper edge of the receptacle, substantially as specified.

CHARLES STOLBERG.
